UNITED STATES PATENT OFFICE.

WILLIAM P. KELLOGG, OF TROY, NEW YORK.

DESIGN FOR A CURRYCOMB.

SPECIFICATION forming part of Design No. 23,872, dated December 11, 1894.

Application filed July 16, 1894. Serial No. 517,747. Term of patent 14 years.

To all whom it may concern:

Be it known that I, WILLIAM P. KELLOGG, a citizen of the United States, residing at Troy, county of Rensselaer, and State of New York, have invented and produced a new and original Design for Currycombs, of which the following is a specification, reference being had to the accompanying drawing, which shows a view in perspective of a currycomb embodying my new design.

The design for the comb comprises the serrated comb-plates, the handle A—, and connecting shank B—.

The comb-plates have serrated edges C— in the form of concentric circles with a lateral opening C'— common to all the circles.

The circular edges are arranged one within another, with equal spaces C²— between them, and with the corresponding edges C³— of the end-portions of the plates radiating

from the circular portions in closed groups, one group on each of the opposite sides of the opening C'—.

The opening C'— is closed at its outer end by barrier D— between the oppositely located groups of radial edges.

The leading feature of my design comprises the circular comb-plates, one within another, with parallel radial ends closed by the barrier as shown.

What I claim as new, and desire to secure by Letters Patent, is—

The design for a curry-comb as herein shown and described.

In testimony whereof I have hereunto set my hand this 9th day of July, 1894.

WM. P. KELLOGG.
